(57) **CLAIM**

The ornamental design for a luminaire, as shown and described.

DESCRIPTION

FIG. 1 is a front perspective view of a luminaire according to our design;

FIG. 2 is a right elevational view thereof;

FIG. 3 is a left elevational view thereof;

FIG. 4 is a top elevational view thereof;

FIG. 5 is a front elevational view thereof;

FIG. 6 is a bottom elevational view thereof; and,

FIG. 7 is a rear elevational view thereof.

The broken line showing of various features is for the purpose of illustrating unclaimed portions of the luminaire and forms no part of the claimed design.

The luminaire is shown with a symbolic break in its length. The appearance of any portion of the article between the break lines forms no part of the claimed design.
